BEVERAGE DISPENSING FAUCET

Richard M. Lowry, Columbus, Ga., assignor to Nehi Corporation, Columbus, Ga., a corporation of Delaware

Application July 26, 1950, Serial No. 11,411

Term of patent 14 years

(Cl. D2—3)

To all whom it may concern:

Be it known that I, Richard M. Lowry, a citizen of the United States, residing at Columbus, Georgia, have invented a new, original, and ornamental Design for a Beverage Dispensing Faucet, of which the following is a specification, reference being had to the accompanying drawing forming a part thereof.

I claim:

The ornamental design for a beverage dispensing faucet, substantially as shown.

RICHARD M. LOWRY.
